UNITED STATES PATENT OFFICE.

JOHN J. KELLUM AND WILLIAM E. HEIDDELESTON, OF RED LODGE, MONTANA.

EMERGENCY-BRAKE.

1,309,945.

Specification of Letters Patent. Patented July 15, 1919.

Application filed May 25, 1918. Serial No. 236,563.

To all whom it may concern:

Be it known that we, JOHN J. KELLUM and WILLIAM E. HEIDDELESTON, citizens of the United States, residing at Red Lodge, in the county of Carbon and State of Montana, have invented certain new and useful Improvements in Emergency-Brakes, of which the following is a specification, reference being had therein to the accompanying drawings.

This invention relates to an emergency brake, and has for its object the improvement of the construction of a brake that is very efficient in operation for preventing an accident on a hill or a mountain grade should the ordinary brakes refuse to work or operate satisfactorily for preventing the car from backing down the hill or grade or over the side of an embankment.

With this and other objects in view, the invention consists of certain novel constructions, combinations, and arrangements of parts, as will be hereinafter fully described and claimed.

In the drawings:

Figure 1 is a view in side elevation of a mechanism constructed in accordance with the present invention.

Fig. 2 is a vertical sectional view taken on line 2—2, Fig. 3, and looking in the direction of the arrows.

Fig. 3 is a vertical sectional view on line 3—3, Fig. 2, and looking in the direction of the arrows.

Fig. 4 is a longitudinal sectional view of the plunger casing.

Referring to the drawings by numerals, 1 designates the hub of a wheel, which is secured to the axle 2. The roller-carrying plate 3 is fixedly secured, through the medium of bolts 4, to the hub 1 of the wheel, and in the receiving pockets 5 of the roller-carrying plate 3 are positioned rollers 6. The pockets 5 are provided with an inclined bottom 5^a that produces a cam-like surface over which each roller 6 travels, so that when the wheel of which the hub 1 is a part, is rotating forwardly, the rollers 6 will rest in the largest part of each pocket 5 (Fig. 2), thereby not locking the wheel upon the axle 2 when the wheel is moving forwardly. However, when the wheel accidentally begins to move backwardly, in

the direction of the arrow (Fig. 2), this will cause the loose socketed ring 7 to rotate sufficiently to cause the rollers 6 to ride forwardly on the inclined faces 5^a of the pockets 5, thereby locking the ring 7 rigidly upon the axle 2 and permitting the inner ends of levers 8 to drop in notches or sockets 9 formed in the loose ring 7.

Each lever 8 is provided with an elongated slot 10, and through slot 10 extends a pin 11, which pin 11 is secured to the guiding ring 12; this guiding ring 12 is secured in place by means of brackets 13, and the object of the ring 12 is to positively guide the levers 8 into the notches 9 of the loose ring 7.

A brake band casing 14 is secured to the rear axle casing 15 by any suitable means, as designated at 16, and within the brake band casing or drum 14 is positioned the split friction or brake ring 17, which split brake ring 17 is provided with lugs 18, at its ends (Fig. 2), and intermediate its ends, is an auxiliary lug 19. A pair of yieldable lever-supporting bars 20 are attached, at their inner ends, at 21, to the auxiliary lug 19 of the brake ring 17, and the outer ends 22 of these lever-carrying bars are pivotally connected, at 22, to the primary lugs 18. Each lever-carrying bar is provided intermediate its ends with a plurality of lugs 23, to each of which lugs 23 is pivotally attached, at its inner end 24, a pivoted lever 8.

Upon the inner ends of levers 8, riding into the sockets or notches of the loose ring 7, after said ring, through the medium of said rollers 6 binding in pockets 5, have locked ring 7 upon axle 2, the levers 8 will jam or force the lever-carrying bars 20 outwardly, thereby jamming or "braking" the split brake rim 17 against the inner face of the brake drum or casing 14, thereby securely fastening the rear wheels against rotary movement backwardly down a grade or hill, even though the emergency brake lug 25 (Fig. 2) and its coöperating parts fail to work.

In case it is desired to back the automobile, this is provided for by connecting rod 27 in any suitable manner with the transmission, (located in container 26, Fig. 1), which rod 27 is provided at its inner end

with a plunger head 28, and plunger head 28 is positioned in the plunger casing 29, and plunger casing 29 is secured to the rod 30. Rod 30 is pivotally connected to one end of the pivotally mounted link 31, and to the opposite end of link 31 is pivotally secured rod 32, which rod 32 is pivotally secured, at 33, to the rotatably mounted guiding ring 12, so that when the operator 5 deliberately shifts the gears of the automobile to cause the motor to drive the car backwardly, through the medium of rods 27, 30 and 32, lever operating ring 12 will cause the outer ends of levers 8 to be positioned away from the loose ring 7 so as to not lock the rear wheels against backward movement. It is to be noted that the 10 brake drum or casing 14 is provided with an elongated slot 34, in which works the extension 33 that is connected directly to the lever guiding ring 12. Each lever 8 extends through a slot 35, in the guiding ring 12 (Fig. 3).

A coil spring 36 is attached to the lever 15 guiding ring, at 37, and its opposite end is attached, at 38, to the auxiliary lug 19 of the brake ring 17. This spring 36 serves to cause the levers 8 to ride quickly into the notches 9 when the split ring 7 is locked 20 upon plate 3 by the action of the rollers 6.

We claim—

1. In a mechanism of the class described, the combination with an axle, of a roller-carrying plate positioned upon said axle, a 25 hub secured to said axle, said plate fixedly secured to said hub, said plate provided with roller-receiving pockets, rollers in said pockets, a loose ring provided with notches engaging said rollers and adapted to be locked 30 against rotary movement upon said plate by said rollers, a brake drum secured upon said axle, a split brake ring in said drum, said brake ring provided with lugs at its ends and a lug intermediate its ends, lever-carrying 35 bars pivotally connected to said lugs of said brake ring, a rotatably mounted lever guiding ring surrounding said loosely mounted notched ring, and levers engaging said loosely mounted guiding ring and pivotally connected at one end to said lever-carrying bar and being adapted to enter 40 said notches on said loosely mounted ring for expanding said brake ring for locking the brake drum against rotary movement in 45 one direction, when the braking action occurs causing the axle, roller-carrying plate, rollers and loose ring to be locked against independent rotary movement.

2. In a mechanism of the class described, 50 the combination with a wheel structure having an axle attached thereto, a brake drum carried by said axle, of a roller-carrying plate secured to said wheel structure, and means including pivotally mounted levers 55 cooperating with said roller-carrying plate

and said brake drum for locking the brake drum and plate and wheel structure against independent rotary movement and also against rotary movement in one direction.

3. In a mechanism of the class described, 70 the combination with a wheel structure provided with a roller-carrying plate, an axle extending through said plate, a brake drum mounted upon said axle, a split ring in said brake drum, yieldable bars pivotally connected at their ends upon said split ring, levers pivotally connected at their inner ends to said bars, guiding means connected to all of said levers, a loosely mounted notched ring surrounding said roller-carrying plate 75 and adapted to receive said levers in its notches, and rollers interposed between said plate and said loosely mounted ring.

4. In a mechanism of the class described, 80 the combination with a hub structure having an axle attached thereto, of a brake drum carried by said axle, a slotted guiding ring supported within said brake drum, levers extending through the slots of said ring, means attached to said levers on the 85 outside of said ring and being adapted to bind against the brake drum, and means carried by the axle and hub structure for engaging the inner ends of said levers within 90 said guiding ring for actuating the levers 95 for causing said binding action upon the brake drum when said hub structure accidentally rotates in one direction.

5. In a mechanism of the class described, 100 the combination with a hub structure provided with an axle, of a brake drum carried by said axle, means including a guiding ring for locking said hub structure against independent movement with respect to said 105 brake drum, an extension carried by said guiding ring, said brake drum provided with an elongated slot through which said extension projects, a link connected to said extension outside of said drum, and a transmission controlled rod and plunger device pivotally connected to said first-mentioned rod 110 for automatically controlling the operation of said locking means within the brake drum.

6. In a mechanism of the class described, 115 the combination with a hub structure, including an axle, of a brake drum carried by said axle, a split ring within said drum, lever-carrying bars pivotally mounted at their ends upon said split ring, each bar provided with depending lugs, slotted levers 120 pivotally secured at their outer ends to the lugs of said bars, brackets secured to said brake drum, a slotted guiding ring slidably mounted upon said brackets, said levers extending through said slots of said guiding ring, means extending through the slots of the levers and through the slots of said guiding ring for slidably connecting said levers 125 and guiding ring, and means carried by said 130

hub structure and coöperating with the inner ends of said levers for operably engaging said levers for causing the same to be forced outwardly upon said guiding ring for 5 expanding said carrying bars and thereby expanding said brake ring against the brake drum for locking said drum against inde-

pendent movement with respect to said hub structure.

In testimony whereof we hereunto affix 10 our signatures.

JOHN J. KELLUM.

WILLIAM E. HEIDDELESTON.
